UNITED STATES PATENT OFFICE.

THOMAS COULTAS, OF PITTSBURG, PENNSYLVANIA.

EXPLOSIVE VALVE FOR BLAST-FURNACES.

SPECIFICATION forming part of Letters Patent No. 553,956, dated February 4, 1896.

Application filed April 4, 1895. Serial No. 544,408. (No model.)

To all whom it may concern:

Be it known that I, THOMAS COULTAS, a resident of Pittsburg, in the county of Allegheny and State of Pennsylvania, have invented a new and useful Improvement in Explosion-Valves for Blast-Furnaces; and I do hereby declare the following to be a full, clear, and exact description thereof.

My invention relates to explosion-valves for blast-furnaces.

It is well known that in the operation of blast-furnaces there is great danger of gas explosions, which always result in damage to the furnaces and often in loss of life.

The object of my invention is to provide an explosion-valve of such construction and located in such position that it will act immediately the explosion takes place to relieve the pressure and prevent damage to the structure.

To these ends my invention comprises certain improvements in such valves, all of which will be fully hereinafter set forth and claimed.

To enable others skilled in the art to make and use my invention I will describe the same more fully, referring to the accompanying drawings, in which—

Figure 1 is a vertical section of my improved explosion-valve. Fig. 2 is a top view thereof. Fig. 3 is a section on the line 3 3, Fig. 2. Fig. 4 is a view of the upper part of a portion of a blast-furnace with my invention applied thereto.

Like letters indicate like parts in each of the figures.

My invention is applicable to any of the ordinary forms of blast-furnaces. The upper part of such a furnace is illustrated in Fig. 4, in which *a* represents the bell closing the hopper *b* in the ordinary manner and connected by the rod *c* to suitable mechanism for lowering and raising said bell. A charging-platform *d* surrounds the hopper *b*, and around the said platform is the fence *e*.

Leading from the upper end of the furnace is the downtake-pipe *f*, which carries off the gas to the stoves or other point of combustion. A pipe *g* is connected to the downtake *f* at about the highest point in said downtake, just about where it begins to descend. The pipe *g* has the brickwork lining *h*.

An annular valve-seat *i* is attached to the

upper end of the pipe *g*. A valve *k*, of cast-iron or other suitable metal, seats itself on the seat *i*, said valve having openings *l* formed 55 therein, which are controlled by the clack-valves *m*, hinged at *n*. The clack-valves *m* are prevented from swinging beyond a vertical position by the stops *o*. Any suitable number of these clack-valves may be employed. The valve *k* has the tongues *p* formed thereon with openings therein, through which the rods *q* pass. In line with said tongues *p* are the tongues *r r'*, which project from the valve-seat *i* and the pipe *g*. The rods *q* also 60 pass through openings in said tongues *r r'*. Interposed between the lower faces of the tongues *r'* and the nuts *s* on said rods *q* are the springs *t*. These rods form guides for the valve *k* and limit the upward movement 70 of same.

Secured to the pipe *g* is the frame composed of the vertical angle-bars *u*, connected by like horizontal bars *v*.

While the rods *q* in a measure guide the 75 valve *k* as it travels up and down, yet I prefer the additional guides formed by the vertical bars *u*. For this purpose the valve *k* has formed thereon the lugs *w*, which move up and down within the guides formed by said 80 bars *u*.

A lug *x* on the valve *k* has secured thereto a rope or chain *y*, which passes up over a pulley *y'* in the frame, and thence down over the pulley *y''*. A weight *z* is secured to the end 85 of the rope *y*. A shelf *z'*, secured to the pipe *g*, forms a support for the weight *z*. The weight of the valve *k* is sufficient, under the ordinary pressure of the gas in the pipe *g*, to maintain it on the seat *i* and hold the weight 90 *z* in its elevated position.

The weight *z* may be made in sections, and if the pressure in the pipe increases, with a tendency to unseat the valve *k*, one of the sections may be removed.

When the furnace is in operation, under ordinary circumstances, the gas passes down the downtake *f* to the point of combustion, but in case of an explosion within the furnace the valve *k* will be raised by the force of same. 100 The clack-valves *m* will open first and relieve the shock on the valve *k* and consequently the strain on the rods *q*, as said valve will not need to rise so high. The weight *z* will

seat itself on the shelf z' and relieve the valve k . After the pressure occasioned by the explosion has subsided the valve k can lower itself, the weight z preventing it seating itself with any degree of force. The spring t relieves the jar on the valve as it rises. By having the pipe g at the upper end of the 5
downtake f and adjacent to the throat of the furnace when an explosion takes place the 10 pressure on the bell and hopper is quickly relieved. Although there are no outlets directly over the charge in the furnace yet the pipe g is sufficiently near to relieve the pressure at once on the parts of the structure above 15 the charge. If the explosion-valve is located within the space above the charge, in case of an explosion the men on the platform are liable to injury. By my invention, however, 20 no injury to the workmen can result.

What I claim as my invention, and desire to secure by Letters Patent, is—

1. In an explosion-valve for blast-furnaces, the combination with the downtake-pipe, of a vertical pipe leading from the upper end of 25 said downtake, a valve at the upper end of said pipe, rods passing through said valve and through projections on said pipe, and springs interposed between said projections, and shoulders on said rods, substantially as 30 set forth.
2. In an explosion-valve for blast-furnaces, the combination with the downtake-pipe, of a vertical pipe leading from the upper end of said downtake, rods passing through said 35 valve and through projections on said pipe, springs interposed between said projections and shoulders on said rods, a weight, and connections between said valve and weight, substantially as set forth.
3. In explosion-valves for blast-furnaces the combination with the downtake-pipe, of a vertical pipe leading from the upper end of 40 said downtake, a valve at the upper end of

said pipe, rods passing through tongues on said valve and through corresponding tongues 45 on said pipe, springs interposed between said last-mentioned tongues and shoulders on said rods, lugs on said valve, uprights extending above said pipe and supported thereby, said uprights forming guides for said lugs, substantially as set forth.

4. In explosion-valves for blast-furnaces, the combination with the downtake-pipe, of a vertical pipe leading from the upper end of 50 said downtake, a valve at the upper end of 55 said pipe, rods passing through said valve and through projections on said pipe, springs interposed between said projections and shoulders on said rods, a frame supported by said pipe, a rope secured to said valve and 60 passing up over a pulley in said frame, a second pulley over which said rope passes, and a weight at the end of said rope, substantially as set forth.

5. In explosion-valves for blast-furnaces, 65 the combination with the downtake-pipe, of a vertical pipe leading from the upper end of said downtake, a valve at the upper end of 70 said pipe, rods passing through said valve and through projections on said pipe, springs interposed between said projections and shoulders on said rods, a frame supported by said pipe, a rope secured to said valve and passing up over a pulley in said frame, a second pulley over which said rope passes, a 75 weight at the end of said rope, and a shelf secured to said pipe and adapted to support said weight when lowered, substantially as set forth.

In testimony whereof I, the said THOMAS COULTAS, have hereunto set my hand.

THOMAS COULTAS.
